CLAIM

The ornamental design for a video camera stand, as shown and described.

DESCRIPTION

FIG. 1 is a first perspective view of a video camera stand showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1; and,

FIG. 10 is an enlarged view of the selected portion 10 in FIG. 1.

The broken lines shown in the drawings depict portions of the video camera stand that form no part of the claimed design. The dash dot dash broken lines shown in FIG. 1, FIG. 9 and FIG. 10 are for the purposes of disclosing areas of enlargement that form no part of the claimed design.

1 Claim, 10 Drawing Sheets(56)
